HEEL PAD

Meyer Margolin, Elgin, Ill.

Application August 28, 1940, Serial No. 354,496

8 Claims. (Cl. 36—3)

My invention relates to a novel heel pad and more particularly my invention relates to a pad to be employed in the heel area of a shoe, which pad has such construction as to provide forced breathing in the heel area and desirable resilience for the heel.

The arts have long been concerned with improvements in construction of shoes for the purpose of improving foot comfort. Advances have been made in providing such foot comfort in the forepart area of the shoe, but it has proved difficult to provide the desirable resilience and breathing effects in the heel area because the heel is not flexed in walking as is the forepart of the shoe.

I have devised a novel heel pad construction comprising a pad having grooves which have spaced apart walls and lugs downwardly protruding from such heel pad to provide both increased resilience and springiness, and further to provide a breathing action by forcing a circulation of air in the heel area. To enable the air to circulate from beneath the heel pad to the interior of the shoe, I provide perforations in and through the heel pad.

When employed in combination with the resilient insole such as is more particularly described in my copending applications Serial No. 257,351, Serial No. 290,559 and Serial No. 306,778 of which this is a continuation in part, complete foot comfort from heel to toe is provided with increased resilience and complete breathing throughout the foot area.

Accordingly, it is an object of my invention to provide a novel resilient heel pad.

It is a further object of my invention to provide a novel heel pad adapted to cause forced breathing in the heel area.

It is a further object of my invention to provide a novel heel pad having grooves and perforations located in said heel pad.

It is a further object of my invention to provide a novel resilient heel pad having substantially transverse grooves with spaced apart walls located on the under side of said heel pad.

It is a further object of my invention to provide a novel heel pad having lugs or projections of resilient material downwardly extending from said heel pad.

It is a further object of my invention to provide a novel heel pad having on its under side substantially transverse grooves with spaced apart walls and resilient lugs downwardly depending from said heel pad, which lugs provide forced breathing both from the grooves and

from the air space between the heel pad and the insole.

It is a further object of my invention to provide a novel heel pad having enclosed grooves with spaced apart walls located on the underside thereof and perforations extending through said heel pad to provide for circulation of air.

These and further objects of my invention will be apparent from a consideration of the drawing and the specific description thereof which here follows.

Figure 1 is a plan view of the upper side of the heel pad of my invention.

Figure 2 is a plan view of the lower side of the heel pad of my invention.

Figure 3 is a cross section taken along the line 3—3 of Figure 1.

Figure 4 is a cross section taken along the line 4—4 of Figure 2.

Figure 5 is a plan view of the upper side of a modified form of my heel pad.

Figure 6 is a plan view of the lower side of a modified form of my heel pad.

Figure 7 is a cross section taken along the line 7—7 of Figure 5.

Figure 8 is a cross section taken along the line 8—8 of Figure 6.

Figure 9 is a cross section taken along the line 9—9 of Figure 5.

Figure 10 is a cross section taken along the line 10—10 of Figure 5.

Referring now more specifically to the drawing, in Figure 1 I show a heel pad 11 having perforations 12 which extend through said heel pad 11. On the under side of this heel pad 11 are grooves 14 having spaced apart walls 15 and 16. The grooves here shown are enclosed at the ends by the walls 17 and 18. The enclosed groove defined by the walls 15, 16, 17 and 18 forms an air pocket that materially increases the resilience of the heel pad without weakening it as would be the case if the groove extended to the edge of the heel pad and was not enclosed by the end walls 17 and 18.

The downward pressure of the heel in walking on these heel pads causes the compression of the enclosed groove and thereby causes air to be forced from the enclosed groove to the adjacent perforation 12. Additionally, although the heel pad 11 itself is formed of a resilient material such as cellular rubber the presence of the air pockets formed by the enclosed grooves increases the all over resilience of the heel pad.

As shown these enclosed grooves are located at spaced intervals throughout the length of the

heel pad. Although I have shown the enclosed grooves as extending transversely across the heel pad, it is within the purview of my invention to place these grooves at any angle with respect to the heel pad and, if desired, these enclosed grooves may be formed to interconnect with one another or they may be formed to connect with the perforations 12.

Further as shown below in connection with Figure 7, it is within the purview of my invention to place perforations in the enclosed groove 14 itself so that air may be forced directly from the enclosed groove through the perforation located therein to the foot.

In Figures 3 and 4, the cross sectional views there presented show the construction of the grooves and perforations with respect to the heel pad and it is to be understood that these grooves can be varied in size and shape, but it is desirable that the walls of the grooves be spaced apart so as to provide the air pockets whose function is above set forth.

In Figure 5 I show the upper side of a modified form 20 of the heel pad of my invention, and this modified form will be more apparent from a consideration of Figures 6 to 10 in which the modified construction is more fully set forth.

In Figure 6 can be seen the underside of this modified heel pad 20 in which are enclosed grooves 21 and perforations 22. Located in the groove 23 are lugs 24 adapted to downwardly project from the heel pad as more particularly shown in Figures 7, 8 and 9, and these lugs bear against the insole or shoe portion on which the heel pad rests.

I further provide lugs such as 26 which are positioned between the grooves 27 and 28. Both the lugs 24 and 26 exert a positive action in increasing both the resilience of the heel pad and in providing forced breathing in the heel area. The lugs 24 when compressed temporarily deform the enclosed grooves 23 and when pressure is lifted from the lugs, the grooves return to their normal shape and circulation of air from the groove results. In the case of the lug 26, the compression of this lug tends to inwardly compress the adjacent grooves 27 and 28 and upon release of pressure from the lug 26, the grooves 27 and 28 return to their normal shape. This deforming and compression of the grooves 27 and 23 and subsequent return to their normal shape also causes air to flow therefrom through the perforations to the interior of the shoe.

Additionally the downwardly projecting lugs 24 and 26 provide an air pocket or air space between the pad 20 and the insole or shoe portion directly beneath the pad. Upon heel pressure being exerted thereon, the lugs 24 and 26 are compressed longitudinally, reducing the size of the air pocket between the heel pad and the insole positioned therebeneath and air therefrom is forced through the perforations in the heel pad to the shoe interior.

Although I have shown these lugs as in the form of rod-like downward projections, it is within the purview of my invention to form the downward projections in the shape of bars. That is, the projections have a large dimension in one direction relative to a lesser width. When such bars are used, a lesser number of projections are necessary than when the rod-like downward projections are employed. The base or bottom of these bars may be dished out to provide the resilience and breathing afforded by the inverted cup shaped base of lug 26.

The lugs may be of various sizes and shapes depending upon the breathing action desired, but it is important that sufficient lugs be employed so that there is no unevenness or bumpiness in the heel pad.

As exemplified in groove 30, the grooves may contain therein perforations 31 which extend from the top of the groove to the top of the pad. Through these perforations 31 air moves directly from the groove to the shoe interior.

In Figure 7 I show in cross section the relative position of the grooves, lugs and perforations of my heel pad.

In Figure 8 I show the lugs 24 located in the grooves 23. As shown in Figure 7 the bottom of the lugs may be of a cup shape and this cup shaped end provides increased resilience and breathing effects since upon compression of the lug by the heel greater downward movement is obtainable since the cup shaped end tends to spread out. This increased downward movement also provides increased breathing in addition to increased resilience since air is forced out from the cup enclosure and hence adds to the air pressure generated by my construction and further the increased distance that the heel pad is forced down increases the compression on the air in the grooves and in the space between the heel pad and the insole on which it rests.

In Figures 9 and 10 I show cross sections to more fully set forth the construction of my novel heel pad and specifically in Figure 10 I show the perforations 31 which connect the grooves 30 with the interior of the shoe.

It is to be understood that proper air communication is to be provided between this heel pad and the shoe interior. This can be effected even with a cover for the heel pad, but the cover must be capable of air communication and this may be provided by providing a porous cover member or by providing perforations in the cover member which correspond with and co-act with the perforations in the heel pad.

By means of the constructions above set forth I have provided a novel heel pad in which the combination of the grooves, lugs and perforations effects a very desirable resilience and breathing action in the heel area. This breathing action is accomplished without the flexing of the unit and is based on only the downward compression of the heel pad by the heel. The downwardly projecting lugs in combination with the grooves act in at least two ways to provide this increased resilience and breathing. As pointed out the lugs not only provide an air pocket between the heel pad and the shoe portion therebeneath but also by their compression and deforming action on the grooves cause air movement therefrom.

Although I have shown my grooves as being substantially rectangular in cross section and thus having straight side walls, it is within the purview of my invention to modify the shape of these grooves, but it is essential that the grooves be such that the long walls thereof are spaced from one another.

Various modifications of this heel pad construction and the combination of elements I have shown will be apparent to those skilled in this art. I intend, therefore, to be limited not by the specific description thereof as set forth hereinabove, but only by the claims hereto appended.

I claim:

1. A heel pad comprising a rubber-like material, grooves located in the bottom of said rubber-

like material, the walls of said grooves being spaced apart from one another, the ends of said grooves being closed, and downwardly extending projections located between said grooves.

2. A heel pad comprising a rubber-like material, and grooves located in the bottom of said rubber-like material, the walls of said grooves being spaced apart from one another, the ends of said grooves being closed, and downwardly extending projections located over said grooves.

3. A heel pad comprising a rubber-like material, grooves located in the bottom of said rubber-like material, the walls of said grooves being spaced apart from one another, perforations communicating with the top of said heel pad located in said rubber-like material between said grooves, and downwardly extending projections of resilient material located on the bottom of said heel pad.

4. A heel pad comprising a rubber-like material, grooves located in the bottom of said rubber-like material, the walls of said grooves being spaced apart from one another, perforations communicating with the top of said heel pad located in said rubber-like material, and downwardly extending solid projections of resilient material located on the bottom of said heel pad, said downwardly extending projections having a base terminating in an inverted cup shape.

5. A heel pad comprising cellular rubber having the general contour of a heel, grooves located in the bottom of said heel pad, said grooves having a substantially rectangular cross-section, the walls of said grooves being spaced apart from one another, the ends of said grooves being closed, a plurality of downwardly extending projections of resilient material located on the bottom of said heel pad, said downwardly extending projections resting on an insole to provide an air space between said heel pad and said insole, perforations through said heel pad providing for

the transmission of air from said grooves and said air space to the interior of the shoe above said heel pad.

6. A heel pad comprising cellular rubber having the general contour of a heel, grooves located in the bottom of said heel pad, said grooves having a substantially rectangular cross-section, the walls of said grooves being spaced apart from one another, a plurality of downwardly extending projections of resilient material located on the bottom of said heel pad, said downwardly extending projections resting on an insole to provide an air space between said heel pad and said insole, perforations located in said grooves providing for the transmission of air from said grooves and said air space to the interior of the shoe above said heel pad.

7. A heel pad comprising cellular rubber having the general contour of a heel, grooves located in the bottom of said heel pad, said grooves having a substantially rectangular cross-section, the walls of said grooves being spaced apart from one another, a plurality of downwardly extending solid projections of resilient material located on the bottom of said heel pad, said downwardly extending projections having a base terminating in an inverted cup shape, said downwardly extending projections resting on an insole to provide an air space between said heel pad and said insole, and perforations through said heel pad providing for the transmission of air from said grooves and said air space to the interior of the shoe above said heel pad.

8. A heel pad comprising a rubber-like material, grooves located in the bottom of said rubber-like material, the walls of said grooves being spaced apart from one another, and downwardly extending projections located in a portion of said grooves, said downwardly extending projections extending beyond the bottom of the heel pad.

MEYER MARGOLIN.
